UNITED STATES PATENT OFFICE.

WILLIAM E. FICKLEN, OF NEW YORK, N. Y.

METAL PROTECTING DEVICE.

1,278,899.

Specification of Letters Patent. Patented Sept. 17, 1918.

Original application filed August 21, 1909, Serial No. 513,920. Divided and this application filed May 27, 1912. Serial No. 699,937.

To all whom it may concern:

Be it known that I, WILLIAM E. FICKLEN, a citizen of the United States, residing at New York city, county of New York, and 5 State of New York, have invented certain new and useful Improvements in Metal Protecting Devices, of which the following is a specification.

My invention relates to metal protecting devices, for the edges of concrete curbs, gutters, and paving, and for other purposes. The present application is a division of my co-pending application Serial #513,920, filed August 21, 1909. Said application has 15 since matured into my Patent No. 1,098,792, granted to me June 2, 1914. Therein I have obtained claims covering the general construction of a street pavement, roadway or the like consisting of a number of sections with reinforced upper edges. In this application I seek to protect the means by which said reinforcing of the edges of concrete sections making up such a roadway or street pavement is effected.

25 One object of my invention is to provide an edge protecting device, simple in construction and easy to set, and one which readily becomes interlocked or interwoven with the concrete in such a way that while 30 parts of my protecting device enter the mass of concrete, portions of said mass enter openings in the protector whereby the concrete and the protecting bar are doubly interlocked. My bar need not be of heavy material but it should be of sufficient thickness 35 and strength to receive and transmit to and distribute among the mass of the curb, road section, or other object with which it is combined and of which it forms a part, the 40 shocks and jars of vehicular or other traffic and pounding.

It provides a binding for the edges of each unit of paving or structure whereby said unit may as a whole expand or contract 45 under climatic changes without affording opportunity for checks and cracks to start from the edges exposed and spread through the mass. Pavements of this type are usually laid in large sections.

50 The above and other objects of the invention will more fully appear upon reference to the accompanying drawings, in which—

Figure 1 is a view in cross-section through 55 a portion of a roadway having a pavement

equipped with the edge protecting members of the present invention.

Fig. 2 is a plan view of the roadway shown in Fig. 1.

Fig. 3 is a front view of a broken length 60 of the protecting member.

Fig. 4 is an end view of one of the protecting members.

Referring to Figs. 3 and 4 the protector is shown as an angle bar, the wings 1 and 65 2 of which are cut at intervals to permit tongues or lugs 3 and 4 to be turned out of the same. In the form of the invention shown in the drawings, the cuts defining the sides of the tongues are made in planes 70 perpendicular to the lengthwise direction of the angle irons; and the cuts defining the distal ends of the tongues are near the bend in the iron. The tongues therefore connect with the wings near the periphery of 75 the latter, permitting the tongues or lugs to be turned to a position remote from the corner, or bend, of the protecting bar, so as to provide a relatively deep anchorage in the concrete or other material of which 80 the pavement or curb is composed. Furthermore, the position of the tongues is such as not to interfere with ready access of the concrete to the extreme inner corner or bend of the bar when the latter is positioned 85 in the unset concrete. Some of the tongues (3) are turned to a different angular position from that of other of the tongues (4). Looking toward the end of bar (see Fig. 4) the tongues 3 and 4 taken together show a 90 V or wedge shaped outline, expanding or diverging toward the interior of the curb or paving block, to offer a greater resistance to outward displacement or withdrawal of the bar than would be the case if all the 95 tongues were turned into the same plane.

The holes or openings 5, which are formed when the tongues are turned out, have several important functions. In forcing the protectors to position in the unset concrete 100 or in flooding the concrete against the bar, the holes 5 provide view points through the bar so that the level of the concrete below the same can be observed, and the workman thus enabled to know when the bar has been 105 moved to its proper position, or the concrete properly flooded into place. The holes are really automatic indicators of the true position of the bar, because the relative position of bar and unset concrete is changed 110

until the latter oozes through the holes and, at these points, becomes flush with the outer surface of the protector. The holes also of course provide for the ready escape of the 5 air under protector as the latter is brought to position.

The protrusions of concrete through the holes to the outer surface of the protector offer a close succession of rough surfaces 10 which provide secure footing for horses' hoofs and other traffic. This is important, as otherwise, and as actually is the case with certain protectors now in use, the smooth surface of the iron, particularly in 15 wet weather, is ineffective to prevent slipping. Again, the interlocking of the concrete with the protector, by reason of the holes in the latter, provides an anchorage which supplements the anchorage afforded 20 by the members 3 and 4, and which is particularly effective in assisting to resist longitudinal displacement of the bar, and this is true where the concrete is exposed within 25 in the expansion joint through the openings in the wing 2.

In Figs. 1 and 2 the protector is shown as applied in pairs to the opposing corners of the pavement blocks 6 and 7 at the expansion joints 8. The openings 5 in the 30 protector, with the concrete therein, are also distinctly shown in Fig. 2. In Figs. 1 and 2 the protector is also shown as applied to the edge or corner of a sidewalk member 10 to serve as a curb nosing.

35 The application of the invention to gutter edges, crossing, and building blocks, etc., will be readily understood. When the protector is in place, and the concrete has set, the tongues from one wing, by extending 40 toward those of the other wing, together form almost continuous bars behind the concrete within the angle iron, thus effectively locking the protector against displacement.

45 The structure shown in the drawings can obviously be modified to a considerable degree, within the scope of the invention. The bar can also be placed so that one wing, only, lies at the surface of the protected 50 structure; the other wing being directed into the structure.

What I claim is:

1. An edge protecting bar for the edges of sections of hydraulic concrete sheet 55 pavements when said pavements are made in large sections, which protector consists of a metal strip adapted to be set flush with a face of a section, said strip provided with tongues cut therefrom and bent away 60 therefrom on one side, thus providing anchoring means extending away from one face only of said strip and leaving openings into which concrete may flow, interweaving and interlocking of the concrete and strip 65 being thus effected.

2. A sheet concrete road or pavement reinforcing strip or bar provided with parts sheared therefrom and bent away therefrom in the direction of the concrete and forming anchoring tongues and supporting 70 shelves, the strip itself forming substantially a face plate adapted to remain at the face or surface of the concrete and not itself substantially to enter the concrete save by said sheared parts and adapted to 75 remain supported by and reinforcing the face thereof, the concrete and the plate mutually interweaving and interlocking.

3. An edge protector for concrete pavements or the like consisting of a metal angle bar or strip having anchoring projections formed from the body of the wing at a point close to the apex of the angle, the projections extending substantially at right angles to the wing from which they are 80 formed, and adjacent projections being bent slightly to either side of the perpendicular of the bar.

4. An edge protector for concrete pavements or the like consisting of a metal angle bar, or strip having anchoring projections formed from the bodies of the wing, at a point close to the apex of the angle, the projections extending substantially at 90 right angles to the wing from which they are 95 formed, and adjacent projections being bent slightly to either side of the perpendicular of the bar, the extremities of the projections from one side of the bar being in proximity to the extremities of the 100 projections from the other side of the bar.

5. A corner protector of angular cross section for the edges of concrete provided with wing members, the upper member of which is provided with a series of spaced 105 openings to receive and expose the concrete and thus provide anti-slipping surfaces, and also with means cut out and bent back from said opening for anchoring the protector to the concrete.

6. In a concrete paving surface, a pair of metal protecting members each set flush with a face of and interlocked or interwoven with concrete material on each side of a joint in said concrete paving surface, each of said 115 members being provided with anchoring elements partly cut out of said members and bent to enter the concrete therefrom, thus making recesses into which concrete passes.

7. A corner protector of angular cross section for edges of concrete having wing members, a member of which is provided with partially cut out sections bent from the plane of said member to form anchoring projections, openings being thus provided to receive and expose the concrete, for the purpose of providing anti-slipping surfaces.

8. A corner protector of angular cross section for the edges of concrete having 130

wing members, one of which is provided with pairs of partially cut out sections, each of which is bent to lie in a different plane from the other, and from the plane of the 5 member from which they are cut, to form anchoring projections to secure the protector to the concrete.

9. An edge protector for concrete pavements and the like, consisting of a metal 10 bar or strip having anchoring tongues or projections cut out therefrom at intervals therealong, thus providing surrounding openings therethrough to receive and expose the concrete to assist in anchoring the strip 15 to the concrete, and provide anti-slipping surfaces.

10. An edge protector for concrete pavements and the like consisting of a metal bar or strip having tongues or projections cut 20 out therefrom at intervals therealong thus providing surrounding openings therein, the tongues to project into the body of the concrete, and openings to receive and expose the concrete, to anchor and secure the strip 25 to the concrete, and provide anti-slipping surfaces.

11. In a concrete paving element and in combination with the pavement, a metal protecting strip set flush with a face of said 30 element, and embedded in the material of said element, said strip being provided with tongues sheared therefrom and bent away therefrom to enter the concrete and to provide openings into which the concrete enters 35 whereby a double interlocking or interweaving bond is formed between the concrete and the strip.

12. In a concrete paving element and in

combination with the pavement, a metal protecting member or strip set flush with a face 40 of and interlocked or interwoven with the concrete material of such an element, the strip being provided with anchoring elements partly cut out and bent to enter the concrete therefrom thus making openings 45 into which concrete is forced.

13. An edge protector for concrete pavements and the like consisting of a metal bar or strip adapted to set flush in a face or 50 faces of the concrete and having tongues or projections cut out from the flush set portion or portions thereof at intervals therealong, thus providing surrounded openings therein, the tongues to project into the body of the concrete, and the openings to receive 55 the concrete, to anchor and secure the strip to the concrete.

14. A pavement edge reinforcing means adapted to form an integral part of a concrete pavement section, comprising an extended strip or web of metal and cut out 60 of and bent back in the direction of the concrete pavement section thereby forming elongated tongues, said tongues being cut wholly out of said strip or web so as to leave 65 inclosed openings into and through which concrete may pass while fluid whereby through the agency of said tongues the concrete and the protecting bar are mutually 70 interlocked or interwoven into one.

Signed by me at New York city, N. Y., this 24th day of May, 1912.

WILLIAM E. FICKLEN.
